UNITED STATES PATENT OFFICE.

ANDREW JAMES JOHNSTON, OF LIVERPOOL, ENGLAND.

MEASURING AND BAG-FILLING APPARATUS.

SPECIFICATION forming part of Letters Patent No. 739,602, dated September 22, 1903.

Application filed August 25, 1902. Serial No. 120,960. (No model.)

To all whom it may concern:

Be it known that I, ANDREW JAMES JOHNSTON, provision merchant, a subject of the King of Great Britain, residing in Liverpool, 5 in the county of Lancaster, England, (whose full postal address is 138 Mill street, Liverpool, aforesaid,) have invented certain new and useful Measuring and Bag-Filling Apparatus, (for which application has been 10 made in Great Britain, No. 2,488, dated January 30, 1902,) of which the following is a specification.

The filling of small bags of sugar, tea, cereals, and other substances of a granular and 15 pulverulent nature and weighing them on scales, so as to contain the exact quantity required, has hitherto been a very tedious and laborious process.

My invention consists in providing an apparatus wherein given quantities of such substances can be measured automatically and filled into bags or other receptacles required with much greater economy of time 20 and labor than by the usual hand method.

The invention will be understood from the following description, reference being had to the accompanying drawings, in which—

Figure 1 is a general view of the machine in perspective; Fig. 2, a vertical section; 30 Fig. 3, a detail view, on an enlarged scale, of the upper valve and mechanism for operating same; Fig. 4, a detail view, on an enlarged scale, of the lower valve; Fig. 5, a detail view of an auxiliary measuring device.

A is a hollow cylinder or container having an outlet-valve B and an inlet-valve C. D is a hopper for filling said container A with the material required to be measured. These valves are alternating ones—that is to 40 say, when one has closed the other opens, and vice versa, so that material is fed into the container from the hopper D, (which can be adjusted to hold any given quantity,) and when full the inlet-valve C is closed to cut 45 off the supply and the outlet-valve opened to discharge the measured material through spout E into a bag or other receptacle.

F is a plate capable of vertical reciprocation in guides f; G, a pair of shutters forming the valve C; H, stems projecting from the shutters G, which are pivoted at h and engage a cam-slot I. They are guided by

guides g. The cam-slot I bifurcates at one point into two separate slots i i. Plate F is connected to and operated by a rod J, worked 55 by a treadle K or handle. By depressing the treadle or handle, therefore, the plate F slides upward and the slots i converging together into the slot I cause the stems to come together, thus closing the shutters G, as shown 60 in Fig. 3. The release of the treadle causes the plate F to descend into the position shown in Fig. 2, thus causing the shutters G to separate, thus opening the valve and permitting the material in the hopper D to flow into 65* the container A. At one point in its length the rod J is provided with a toothed rack L, and this rod is provided with a sliding carriage M, having a pivoted arm N, which engages, by means of a detent, the teeth of the rack L, so 70 that it engages the teeth at any point in the length of the rack. The arm N being pivoted to the detent can be lifted clear of the teeth of the rack and enable the carriage to be adjusted in its position. The valve B is hinged 75 and has a projecting arm O at rear, and this hinge is provided with a spring P, so that when the force that opened the valve is removed the valve will normally close by the action of the spring P. When the rod J rises 80 and has nearly finished its stroke, this bracket N strikes the arm O, and thus opens the valve B, which then assumes a sloping position (shown in Fig. 4) and causes the material contained in the container to flow out 85 into the bag or other receptacle underneath through the chute E. The closing of the valve takes place, however, before the arm N arrives at the valve-arm O, this being effected by the special shape of the cam-slots i I. The 90 container A, which measures the quantity of sugar or other granular material, is made adjustable, so as to measure any given quantity or quantities required. For this purpose the container A is made telescopic—that is 95 to say, one part slides within the other part, the upper remains stationary, while the lower part, which is of larger diameter, is adapted to slide up and down outside it, and thus increase or decrease the container's interior 100 capacity—and it is guided by the guide-rods W, being provided with lugs X sliding up and down these rods W. This lower part has projections Q, through which passes a

screwed spindle R. By turning the handle S the lower part of the container can be raised or lowered, and thus decrease or increase the capacity thereof, and this capacity 5 can be adjusted to a great nicety. After adjustment of the lower part of the container A the bracket N is also adjusted in its position, so as to strike the valve-arm O immediately before the completion of the stroke of 10 the rod J. This is effected by simply disengaging the detent from the teeth of the rack and then sliding the carriage M either higher or lower, as required.

For the purpose of increasing the extent 15 of variations in the measuring capacity of the container I provide outside the upper part of the container A a tube a, and outside this again a tube a', both arranged telescopically. The upward movement of the lower 20 part of the container will first raise the part a' and subsequently part a, thus greatly decreasing the effective capacity of the container A when it is required to deliver small measured quantities of material. The lowering of A will liberate the parts a a', and they will thus fall by their own weight into the position shown in Fig. 2.

When the machine is required to measure 25 smaller quantities of material than the container A is designed to hold, I provide an auxiliary container T, Fig. 5, which is inserted in the inside of the upper part of the main container A. Projecting pins U on the projecting flange of this auxiliary container fit into corresponding slots V, Fig. 2, and hold it in position. The upper part of 30 the container A is supported in guides w in the machine-frame in such a manner that by sliding the upper part a laterally it will clear 35 the frame and enable it to be entirely removed. This facilitates cleaning, and it also facilitates the auxiliary container T being inserted, and the container A, with its auxiliary one T can then be replaced in the guides 40 w of the frame. The hopper D is bolted at Y to an arm of the frame. The lower valve is 45 provided with bayonet-slots Z, in which engage pins on the movable part of the container A. Thus by giving this valve a slight 50 turn it will become disengaged from the pins and enable the entire lower valve to be removed when it is required to clean or repair the interior of the container.

In thus describing my invention I wish it 55 to be understood that I do not confine myself to the exact details described, as alterations can be made without departing from the nature of the invention.

Fig. 1^a shows a simple construction of the 60 arm N, which is also adjustable, lugs m being provided thereon to slidily embrace the rod J, the fixing in position being effected by set-screw o. The arm O has play between the projection N and a stop n, which 65 is restricted by pin p.

I declare that what I claim is—

1. In apparatus for measuring sugar, tea,

and other materials of a granular or pulverulent nature and filling them into bags or other receptacles, the combination of a pair of shutters adapted to separate to open the inlet to the container, or close together when it is required to close it, a hinged valve at bottom of said container held normally closed by a spring, a vertical moving rod, means for actuating said rod, a projection on said rod, an arm on said hinged valve with which the projection engages, and a cam device on said rod adapted to operate said shutters to open them subsequent to the outlet-valve being closed or 80 close them previous to it being opened, substantially as described.

2. In apparatus for measuring sugar, tea, and other materials of a granular or pulverulent nature and filling them into bags or other receptacles, a measuring-container made in parts adapted to slide one inside the others and be adjustable in regard to its internal capacity, in combination with a guiding device adapted to guide the movable part, and 85 means for sliding the parts, said means consisting of a screwed shaft adapted to raise and lower the lower part of the container, and a collar or lid slidably mounted on the upper part of the container restricted as to its downward movement by projections at the lower extremity of the said upper part of the container, substantially as described.

3. In apparatus for measuring sugar, tea, and other materials of a granular or pulverulent nature, and filling them into bags or other receptacles, the combination of a measuring-container made in two parts so as to slide one outside the other, a hinged outlet-valve controlling the outlet of said container, a vertical rod, means for vertically actuating said rod, and a projection on said rod, an arm with which said projection engages on said hinged valve, said projection being adjustable longitudinally on said rod, substantially as described.

4. In apparatus for measuring sugar, tea, and other materials of a granular or pulverulent nature and filling them into bags or other receptacles, the combination of a measuring-container made in two parts so as to slide one outside the other, a hinged outlet-valve controlling the outlet of said container, a vertically-moving rod, means for actuating said rod, a lower projection on said rod together 110 with an upper projection on said rod, an arm on said hinged valve, said arm being adapted to engage between said upper and lower projections, a set-screw on said upper projection adapted to adjust the play of said arm between the said projections, means for adjusting said projections vertically on said rod, substantially as described.

5. In apparatus for measuring sugar, tea or other materials of a granular or pulverulent 115 nature and filling them into bags or other receptacles a main container comprising an upper part and a lower part capable of adjustment the one relative to the other, in combi-

nation with an auxiliary container of smaller diameter and adapted to be mounted within the main container whereby smaller quantities can be measured, substantially as described.

6. An apparatus for measuring sugar, tea, and other materials of a granular or pulverulent nature, and filling them into bags or other receptacles, comprising a container adapted to receive and contain the exact quantity required to be measured, means for feeding the material into said container, an inlet-valve on top of the container, said valve consisting of two shutters G carried by pivotally-mounted stems H, a cam-plate F having a slot I with bifurcations i i adapted to receive the stems H, means adapted to be operated by hand or foot for reciprocating the cam-plate F to open and close the shutters G, an outlet-valve at the bottom of the container and means for opening and closing said outlet-valve in the same movement in such a manner that the inlet-valve is opened subsequent to the closing of the outlet, and closed previous to the opening of the latter, substantially as described.

7. An apparatus for measuring sugar, tea, and other materials of a granular or pulverulent nature, and filling them into bags, comprising a container adapted to receive and contain the exact quantity required to be measured, means for feeding the material into said container, an inlet-valve on top of the container, a hinged outlet-valve in the bottom of the container, a rod adapted to be reciprocated vertically by hand or foot, means adapted to

be actuated by said rod to open and close the inlet-valve, a projection N pivotally mounted on a slide on said rod and having a detent to engage a rack on the rod, an arm on the hinged valve adapted to be engaged by projection N in the reciprocation of the rod to actuate the opening and closing of said hinged valve, the projection N being adjustable longitudinally on the rod, substantially as described.

8. An apparatus for measuring sugar, tea, and other materials of a granular or pulverulent nature, and filling them into bags, comprising a container adapted to receive and contain the exact quantity required to be measured, means for feeding the material into said container, an inlet-valve on top of the container, an outlet-valve at the bottom thereof, said outlet-valve having a bayonet-joint connection to the container, a discharge-chute loosely hung below the outlet-valve on hooked rods carried by projections extending outwardly from upright portions of the frame, and means adapted to be worked by hand or foot to open and close the two valves, the motions being so timed that the inlet-valve is opened subsequent to the closing of the outlet, and closed previous to the opening of the latter, substantially as described.

In witness whereof I have hereunto signed my name, this 12th day of August, 1902, in the presence of two subscribing witnesses.

ANDREW JAMES JOHNSTON.
